UNITED STATES PATENT OFFICE.

BENJAMIN MARSHALL HARRISON, OF LITTLE ROCK, ARKANSAS.

DESIGN FOR A PERPETUAL CALENDAR.

53,500.

Specification for Design.

Patented July 8, 1919.

Application filed April 1, 1919. Serial No. 286,764. Term of patent 7 years.

To all whom it may concern:

Be it known that I, BENJAMIN M. HARRISON, a citizen of the United States, residing at Little Rock, in the county of Pulaski and State of Arkansas, have invented a new, original, and ornamental Design for a Perpetual Calendar, of which the following is a specification, reference being had to the accompanying drawing, forming part thereof.

The figure is a face view of a perpetual calendar, showing my new design.

What is claimed is:

The ornamental design for a perpetual calendar as shown.

BENJAMIN MARSHALL HARRISON.

Witnesses:

J. W. ROBINSON,
P. L. DOOLEY.
